Primary Examiner — Nathan M Johnston(57) **CLAIM**

I claim the ornamental design for an IV pole, as shown and described.

DESCRIPTION

FIG. 1 is a perspective view of an IV pole, showing my new design;

FIG. 2 is a front view thereof;

FIG. 3 is a rear side view thereof;

FIG. 4 is a left side view thereof;

FIG. 5 is a right side view thereof;

FIG. 6 is a top view thereof; and,

FIG. 7 is a bottom view thereof.

The broken line portion of the figure drawings is included to show portions of the article that forms no part of the claim design. The IV pole is shown with symbolic breaks in its height. The appearance of any portion of the article between the break lines forms no part of the claimed design.
